Leo Perry,

BY Leo J. Perry atty

UNITED STATES PATENT OFFICE

134,257

DESIGN FOR A COAT OR SIMILAR ARTICLE

Leo Perry, Whitewater, Wis.

Application January 19, 1942, Serial No. 105,307

Term of patent 7 years

To all whom it may concern:

Be it known that I, Leo Perry, a citizen of the United States, residing at Whitewater, in the county of Walworth and State of Wisconsin, have invented a new, original, and ornamental Design for a Coat or Similar Article, of which the following is a specification, reference being had to the accompanying drawing, forming a part thereof.

Fig. 1 is a front view of a coat or similar article showing my new design; and,

Fig. 2 is a rear view thereof.

I claim:

The ornamental design for a coat or similar article, as shown.

LEO PERRY.
